UNITED STATES PATENT OFFICE.

THOMAS M. EYNON AND JOSEPH W. GAMBLE, OF PHILADELPHIA, PENNSYLVANIA, ASSIGNORS TO THE EYNON EVANS MANUFACTURING COMPANY, OF PENNSYLVANIA.

INJECTOR.

SPECIFICATION forming part of Letters Patent No. 537,279, dated April 9, 1895.

Application filed May 26, 1894. Serial No. 512,504. (Model.)

To all whom it may concern:

Be it known that we, THOMAS M. EYNON and JOSEPH WILLARD GAMBLE, citizens of the United States, residing in the city and county 5 of Philadelphia, State of Pennsylvania, have invented a new and useful Improvement in Injectors, which improvement is fully set forth in the following specification and accompanying drawings.

- 10 Our invention relates to that class of injectors known as the "double tube injector," and our object is to construct a compact and symmetrical injector, embodying all the essential features of Patent No. 497,269, granted 15 to Thomas M. Eynon, as regards accessibility to all portions of the interior, and simplicity of working parts, and to incorporate some additional features, which will be hereinafter referred to.
- 20 Figure 1 represents a longitudinal section of an injector embodying our invention. Fig. 2 represents a horizontal sectional view of the casing, taken on the line x, x , of Fig. 1. Fig. 3 represents a transverse section on line x', x' , 25 Fig. 1. Fig. 4 represents a longitudinal section of an injector, showing the connections for throttling, arranged exteriorly of the injector casing.

Similar letters of reference indicate corresponding parts in all the figures.

Referring to the drawings: A designates the body or casing of the injector; B, the steam inlet; C, the water supply inlet, and D the outlet to the boiler.

- 35 Steam entering at B passes into the chamber E, which is provided with a valve body F, which has a valve seat G, said valve F being hollow and containing a second valve, as will be hereinafter explained, and being adapted 40 to close a passage leading to the forcing steam chamber H, which supplies steam to the forcing nozzle K.

L designates the suction steam chamber, which supplies steam to the suction nozzle M, 45 which is suitably secured to the partition V², the admission of steam to this chamber being controlled by the valve N, which we term the secondary valve. O designates passages leading to said chamber L, as shown in Fig. 3 es-

pecially a communication being effected between said chamber and the chamber E by means of the said passages O, port P and the opening A³, in the valve F.

Q designates an opening in the end of the body F, in which the valve stem R moves freely.

S designates a chamber connecting the discharge end of the suction combining tube T, with the supply end of the forcing combining tube U, into which the nozzle K projects a short distance.

The tube U has its screw-threaded portion R² which engages a partition N² between the chambers S and W. The end S² of the tube U passes through the diaphragm T², substantially sealing the chamber W from the chamber E.

V designates the suction chamber into which the water is first conducted. The tube T is suitably secured at W² to the partition 70 which separates the chamber V from the chamber S.

W designates a chamber having communication with the atmosphere by means of the passage Z, and the cored passages X, which 75 lead downwardly and then turn into the overflow nozzle Y, as shown in dotted lines in Fig. 1, at the right.

Through the chamber W water can escape freely from the suction combining tube T and chamber S' through the check valve A', passages Z and X to the atmosphere when starting the injector.

The check valve A' is located in the partition between the chambers S and W, and has 85 its seat in the screw-threaded ring B', which has the cage C', cast thereon, the valve A' being guided top and bottom by wings.

The plug D' is cast integral with the ring B' and cage C', which extends above and below said ring, and has the openings U² for the passage of fluid. Access can be had to said valve A' and its seat B', and both can be removed at the same time for inspection or repairs, by simply unscrewing the ring B', the plug, seat, valve and cage being withdrawn together, it being noticed that the portions of the plug D' which contact with the injector

casing are unthreaded but form a tight joint with said casing.

5 E' designates a chamber into which the forcing combining tube U discharges, and has communication with the atmosphere by means of the cored passages F' and X.

10 G' designates a handle fulcrumed at H', and connected by the link K' to the plug L', which is screwed into or otherwise secured to the cap M', which is suitably attached to the casing A. The handle G' may be locked in any position by the latch O', which is pressed downwardly by the spring P', so that it can engage in slots in the arc or quadrant R'. 15 The latch O' is raised by pressing the bent lever S', which is pivoted at T', toward the handle G'.

15 U' designates an arm carrying the arc or quadrant R' and is connected to the handle G' by the pin V'. The arm U' is secured to the valve stem R as at Y², and is bored out at Z², so that it can slide on the elongated stuffing box W', which forms a guide for the same, thus relieving the valve stem R from any injurious bending strain.

20 The valve body F which is adapted to be seated at G, is made in the form of a hollow shell or barrel, and is provided with the opening A³ for the admission of steam. In said shell moves the enlarged head X' of the valve stem R, which has suitably secured to it the valve N, which is adapted to close the port P in the valve F, which leads to the chamber O.

25 The port between the chamber H and the passages O, is closed by means of the piston B³, which is integral with the valve body F.

30 The hollow portion of the valve F is made long enough to allow a movement of the enlarged head X' and the valve N, equal to the amount required for regulation, so that the initial movement of the handle G' will move the valve N from its seat, bringing the enlarged head X' against the shoulder inside the valve F, opening the port P, and allowing steam to enter the passages O, and a further movement of said handle will move the valve F from its seat G. The valve F is connected by means of the stems Y' and Z' with the overflow valve A², and the throttle piston B², 35 said stems passing through the stuffing boxes C² and D², which prevent the escape of steam from the overflow while the injector is in operation. The valve N is secured to the enlarged head X' in any suitable manner, in the present instance by a pin E².

40 F² and G² designate plugs in the casing A, by removing which, access can be readily had to the interior.

45 The check valve H² in the discharge opening of the injector is seated on the ring K², which can be readily removed. The ring L² acts as a stop, limiting the movement of said valve which is provided with wings similar to the valve A'. The nozzle K is screwed into 50 the partition M², and extends a short distance into the tube U, which is screwed into the partition N². The valves A² and B² are adapted

50 to open and close the apertures in the partitions O² and P², as will be hereinafter set forth.

55 The operation will now be apparent. Assume the parts to be in the positions shown in Fig. 1. A slight movement of the handle G' to the left, moves the valve N from its seat on the port P, allowing steam to pass from the chamber E, through the passage A³ and port 70 P into the passages O, which lead downwardly into the chamber L. The steam then blows through the suction nozzle M, and the suction combining tube T lifts check valve A' and escapes through the chamber W, 75 passages Z and X into the nozzle Y to the atmosphere. The steam blowing through the nozzles, as just described, produces a vacuum in the chamber V, which causes the water to enter therein, passing thence through the 80 suction combining tube T, condensing the steam in its passage, lifting the check valve A', passing through chambers W, Z, and X, and nozzle Y, and finally making its exit into the atmosphere. A further movement of the 85 handle G', causes the enlarged head X' of the valve stem, to come in contact with the interior of the valve F, withdrawing the same from its seat, but steam is prevented from entering the forcing chamber H by the piston 90 Q² on the valve F, until the piston B² has moved far enough to close the port in the partition P² to the atmosphere. A still further movement of the handle G' allows steam to freely flow into the forcing chamber H, and 95 to enter the forcing nozzle K, pass through the combining tube U, where it comes in contact with a stream of water, which is already being delivered through said combining tube U, by the suction tube T, the speed of the 100 water being accelerated by the steam from the forcing nozzle K. The water is still permitted to escape through the passages E', F' and X, into the atmosphere, but as the valve 105 A² is gradually closed the communication is 110 shut off between the chamber E' and the atmosphere, and the water which has now attained a high velocity, rushes through the tube U, opens the check valve H² and is conducted to the boiler or elsewhere. The injector is now delivering its maximum quantity of water, and if it is desired to regulate the same, the handle G' is moved forward sufficiently to cause the valve N to partially close 115 the port P, thereby throttling the steam entering the suction chamber L, whereby the 120 quantity of water entering the boiler can be reduced fifty per cent. of the maximum capacity.

125 It is of course obvious, that the throttling of the overflow passages may be effected by means of connections direct from the valve stem R, to the valves which control said passages, which connections may extend outside the injector casing if desired.

130 In Fig. 4 I have shown, for the most part in full lines, the preferred arrangement and location of the external connections, the overflow passages being arranged vertically in

the present instance instead of horizontally, as seen in Fig. 1, the object and function however being the same as in said figure.

- A⁴ designates a stud which is attached to some portion of the arm U', and which is engaged by the walls of the slot B⁴, in one end of the bar C⁴, the other end of said bar being pivotally attached to an end of the lever D⁴ by means of a stud M⁴, which latter is attached to a suitable portion of the stem Y', said lever D⁴ being fulcrumed at E⁴, the other end of the same being pivotally attached to a link F⁴, and the other end of the latter being pivotally attached to the arm G⁴ of the bell crank H⁴, the other arm K⁴ of said bell crank being suitably connected in the present instance by an intervening link, to a sleeve L⁴ in the vertically-extending overflow passages, by which means the throttling is effected.
- B³ designates the valve piston which is capable of longitudinal movement as is evident.
- The operation is the same as has already been described, the first movement of the handle G, acting to withdraw the head N, so as to open the port P to live steam which passes into the chamber L, as before, the stud A⁴ moving freely, in the meanwhile, in the slot B⁴. A further movement of the handle G' causes the said stud to contact with the wall N⁴ of the slot B⁴, whereupon by reason of the connection between the bar C⁴ and the stem Y', the head F will be moved from the seat G, thus allowing live steam to flow into the chamber H, the throttling in the meanwhile being simultaneously effected by means of the connections D⁴, F⁴, H⁴ to the sleeve L⁴, the functions of the different parts being the same, and occurring in the same sequence, as has already been described with respect to Fig. 1.

Having thus described our invention, what we claim as new, and desire to secure by Letters Patent, is—

1. In an injector, a casing, a double seated valve body, a suction chamber and a forcing chamber, a secondary valve controlling a passage leading to the suction steam chamber, and the valve body controlling a passage leading to the forcing steam chamber, said valves being connected axially in line with the overflow valve A², and the throttle piston B², said valves A² and B² controlling passages leading from the interior of the casing to the atmosphere, said parts being combined substantially as described.

2. In a double tube injector, a suction chamber, a forcing chamber, steam inlets therefor, a valve device for said inlets, a chamber W having passages leading therefrom to the overflow and main discharge respectively, valves controlling said passages, mechanism for positively actuating said last mentioned valves, by the first mentioned valve device, a chamber S adjacent said chamber W, and a check valve between said chambers, said parts being combined substantially as described.

3. In an injector, a suction steam chamber,

a valved steam inlet therefor, the nozzles M and T, chambers S and W, a check valve between said chambers, a passage leading from said chamber W to the main discharge of the injector, a second passage leading to the overflow, a valve device for said passages and means for positively actuating the same, the above parts being combined substantially as described.

4. In a double tube injector, a double seated valve structure or body, adapted to contact the steam inlets, to the suction steam chamber and the forcing steam chamber respectively, said valve body having the port P leading to the suction steam chamber and controlled by the valve N, the chambers S and W, overflow and discharge passages leading from said chamber, a check valve interposed between said chambers, S and W, a seat B' for said valve, said seat having attached thereto, the cage C' and the plug D' the latter contacting with the injector casing whereby by the removal of said plug, the seat, valve and cage are simultaneously withdrawn, substantially as described.

5. In an injector, the combining tube U, suitably secured in a partition between the chambers S and W, said chamber W having valved passages communicating with, the atmosphere, the discharge end of said tube terminating in a chamber E', and passing through the diaphragm T², whereby the chamber E' is substantially sealed from the chamber W, a suction inlet and a valve controlled steam inlet for said combining tube, said parts being combined substantially as described.

6. In a double tube injector, a double seated valve structure or body adapted to control the steam inlets to the suction steam chamber, and the forcing steam chamber, the said valve body having a port P leading to the suction steam chamber controlled by the valve N, whereby the capacity of the injector may be regulated by a movement of the handle which actuates the whole valve body, in combination with overflow and discharge passages, said parts being combined substantially as described.

7. In a double tube injector, a forcing steam chamber, a suction steam chamber, a double seated valve body F, comprising a suitable shell or barrel having the piston Q² adapted to be seated at G, and the port P controlled by a valve N, said valve structure controlling the passage between said chambers, an overflow leading from the suction chamber S to the atmosphere, and controlled by a valve device A² connected to the valve structure F in such a way that the throttling of said overflow passage is effected simultaneously with the admission of steam to the forcing nozzle K, said parts being combined substantially as described.

8. In an injector, the elongated stuffing box W', adapted to serve as a guide for an arm U', connected to the valve stem R, said arm being suitably attached to a handle G' the

latter having a connection at its end with a fixed point, said parts being combined substantially as described.

9. In an injector, an unthreaded plug, connected by an apertured cage, to a threaded ring, the latter being adapted to engage a partition in said injector, and the plug adapted to engage the injector casing and to form a closure for the same, substantially as described.

10. A plug connected by an apertured cage to a threaded ring, adapted to serve as a valve seat, a check valve provided with wings on each side which serve to guide said valve 15 above and below its seat, said plug, cage and ring being integral, substantially as described.

11. In a double tube injector, a forcing steam chamber and a suction steam chamber, valved steam inlets therefor, a chamber W 20 having a valved passage leading to the overflow, a second chamber E' having also a valved passage leading to the overflow, means for actuating the above valves by one handle, whereby the overflow from a chamber W will 25 first be throttled, then the overflow from the chamber E', substantially as described.

12. In a double tube injector, a forcing steam chamber, a double seated valve body separating said chambers and adapted to control the admission of steam to both, the chambers V, S, W, and E', suction and forcing combining tubes, a check valve between said chambers, and W, overflow passages leading from the chambers W and E' and means for 35 positively controlling and throttling said passages, the above parts being combined substantially as described.

13. In an injector, the casing A, chambers II, O, M, V, S, W, and E' valved passages leading 40 from the last two chambers to the atmosphere, the valve body F constructed as shown, having the stem R, valve N and port P, and connections to valves A², and B², nozzles K and M, tubes U and T, and check valve A', 45 said parts being combined substantially as described.

14. In a double tube injector, constructed substantially as shown, and provided with the adjacent chambers S and W, the check valve

A' adapted to seat on the ring B', said ring 50 having a cage and a plug D' cast integral therewith, said parts being combined substantially as described.

15. In an injector, a suction chamber, a suction combining tube, a forcing combining tube, a chamber S connecting the same, a chamber W through which said forcing combining tube passes, the discharge end of the latter being outside of said chamber, suitable 55 overflow passages, and a check valve located 60 between said chambers and said overflow, substantially as described.

16. In a double tube injector, a forcing and suction steam chamber, a double seated valve structure actuated by the valve stem R for 65 controlling the passage between said chambers, suction and forcing combining tubes, an overflow leading from the suction chamber to the atmosphere, and an overflow passage leading from the main discharge to the atmosphere, valve mechanism for controlling said 70 overflows and adapted to be operated in unison with the valve stem R, substantially as described.

17. In a double tube injector, having a suction combining tube and a forcing combining tube, chambers into which said tubes discharge, a separate overflow passage for each of said chambers, and means for positively 75 throttling said overflow, substantially as described.

18. In a double tube injector, a forcing steam chamber and a suction steam chamber, a double seated valve structure controlling the passage between said chambers, a suction 80 combining tube, and a forcing combining tube, chambers into which said tubes discharge, a separate overflow passage from each of said chambers, and means for positively 85 throttling each of said overflow passages, said 90 means being actuated by the same device which moves said double seated valve structure, substantially as described.
